FURNITURE PULL OR THE LIKE

Roy A. Stone, Rockford, Ill., assignor to National Lock
Co., Rockford, Ill., a corporation of Delaware

Filed Mar. 30, 1964, Ser. No. 79,237

Term of patent 14 years

(Cl. D10—8)

FIG. 1 is a front elevational view of a furniture pull or the like embodying my new design;

FIG. 2 is a top plan view thereof;

FIG. 3 is a rear elevational view thereof;

FIG. 4 is a bottom plan view thereof;

FIG. 5 is an end elevational view thereof; and

FIG. 6 is a cross sectional view thereof on the line 6—6 of FIG. 1.

I claim:

The ornamental design for a furniture pull or the like, substantially as shown.
